UNITED STATES PATENT OFFICE

109,158

DESIGN FOR A BRACELET OR SIMILAR ARTICLE

Joseph F. Stedman, Brooklyn, N. Y.

Application January 29, 1938, Serial No. 74,710

Term of patent 14 years

To all whom it may concern:

Be it known that I, Joseph F. Stedman, a citizen of the United States, residing at Brooklyn, in the county of Kings and State of New York, have invented a new, original, and ornamental Design for a Bracelet or Similar Article, of which the following is a specification, reference being had to the accompanying drawing, forming part thereof.

Figure 1 is a front elevational view of a bracelet, showing my new design,

Figure 2 is a rear elevational view thereof, and Figure 3 is a fragmentary edge elevational view of the same.

The completion of that shown by broken lines in Figures 1 and 3 of the drawing would involve a mere repetition of that disclosed by solid lines in said figures.

I claim:

The ornamental design for a bracelet or similar article, as shown and described.

JOSEPH F. STEDMAN.
